US0D1109277S

(12) **United States Design Patent** (10) **Patent No.:** **US D1,109,277 S**
(45) **Date of Patent:** **** Jan. 13, 2026**

(54) **ANIMAL REPELLENT**

(71) Applicant: **Shenzhen Ruichaoteng Technology Co., Ltd.**, Guangdong (CN)

(72) Inventor: **Jianhui Li**, Guangdong (CN)

(**) Term: **15 Years**

(21) Appl. No.: **29/978,160**

(22) Filed: **Dec. 11, 2024**

(30) **Foreign Application Priority Data**

Jul. 19, 2024 (CN) 202430453121.6

(51) **LOC (15) Cl.** **22-06**

(52) **U.S. Cl.**

USPC **D22/120**

(58) **Field of Classification Search**

USPC D22/119, 120, 122; D26/67; D13/102

CPC A01K 15/023; H02S 40/34; H01L 31/042

See application file for complete search history.

(57) **CLAIM**

The ornamental design for an animal repellent, as shown and described.

DESCRIPTION

FIG. 1 is a front, right and top perspective view of an animal repellent showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the animal repellent that form no part of the claimed design.

1 Claim, 8 Drawing Sheets
